United States Patent Office

Des. 186,044
Patented Sept. 1, 1959

186,044

PIE DOUGH PERFORATOR

Florence E. Hauser, St. Louis, Mo.

Application April 30, 1959, Serial No. 55,720

Term of patent 14 years

(Cl. D44—29)

FIG. 1.

FIG. 2.

FIG. 3.

I claim:

The ornamental design for a pie dough perforator, as shown.
